PROCESSING METAL VAPOR TUBES

Fred M. Johnson, Princeton, N.J., assignor to Radio Corporation of America, a corporation of Delaware

Filed Dec. 26, 1962, Ser. No. 247,059

12 Claims. (Cl. 316—3)

The present invention relates to apparatus for and method of processing gas tubes, such as cesium vapor thermionic energy converters. The invention will be described in connection with such converters with the understanding that it can also be used for processing other types of gas tubes. The term "gas" is intended to include metal vapor.

A thermionic energy converter is an electron tube, having a cathode and anode, for converting heat energy applied to the cathode to electrical energy in the form of a voltage produced by the tube itself between cathode and anode terminals. A typical thermionic energy converter tube comprises a sealed envelope containing a cathode and an anode spaced apart to provide an electron path therebetween. Usually the cathode and anode form parts of, or are in heat transfer relation with, the tube envelope, to permit direct heating and cooling, respectively, of these electrodes by external means. The materials of the cathode and anode are usually chosen such that the effective electron work function of the cathode is substantially higher than that of the anode, to produce an internal electric field for accelerating electrons from the cathode to the anode during short circuit condition. Each electron collected by the anode generates heat energy therein, at least equal to the anode work function. The output voltage V is a function of the load resistance R . If the load resistance is such that the surface potentials of the cathode and anode are equal and there is no internal voltage drop, the output voltage is theoretically equal to the difference in work function of the cathode and anode, and the output power, $VI=R^2I$, is a maximum. In order to approach these optimum conditions, it is necessary to neutralize the space charge of the electrons by use of positive ions. Such ions can be produced in many ways, the best of which is to introduce an alkali metal vapor, such as cesium, having a low ionization potential within the interelectrode space. If the cathode is bare tungsten, for example, having an effective work function (4.5 volts) higher than the ionization potential (3.89 volts) of the cesium operating at temperatures of the order of 2000° K., the cesium vapor atoms coming into contact with the hot cathode are ionized by "contact" ionization. In another mode of operation, known as the "ball-of-fire" mode, the cathode has an effective work function lower than the ionization potential of the metal vapor used, and the vapor atoms are ionized as a result of a complicated process involving successive excitations by electron collisions and photons. For example, the outermost electron in an atom of cesium vapor may be excited by an electron or photon to a higher energy state, and remain there long enough to be further excited by another electron or photon to the next energy state, etc., until it is completely removed from the atom to leave a positive cesium ion. Other electrons, after excitation, return to lower energy states and radiate energy in the form of photons, some of which may in turn produce resonance excitation of other cesium atoms. Most of the resonance excitation occurs between the ground state and the lowest lying excited states, $6P_{3/2}$ and $6P_{1/2}$, because of their greater population density. The lifetime of the various excited states are so short that, for satisfactory operation in the ball-of-fire mode, considerable resonance excitation must be present. Each chain of photon-atom energy transfers should involve a large number of such

2

transfers before it is terminated by a photon being absorbed by the tube wall, for example.

The ball-of-fire mode operation is very sensitive to impurity gases in the converter tube. A converter tube 5 of this type which had deteriorated during use was found to contain argon gas. Other impurity gases, such as oxygen, are also probably detrimental to satisfactory operation in the ball-of-fire mode. It is believed that such impurity gases produce a quenching effect on the excited states of the cesium atoms. For example, the thermal movements of an argon atom, for example, may cause it to collide with, or pass very close to, a cesium atom and produce a change in the frequency of photons radiated therefrom, and thus prevent, or reduce the probability of, 10 excitation of other atoms by such photons by interfering with the resonance phenomenon. The most important excited states in the ball-of-fire mode of operation are the lowest lying excited states, whose atomic lifetimes are of the order of 3×10^{-8} second for cesium. The excited 15 states are most sensitive to impurity atoms.

Other detrimental effects of impurity gases in metal vapor tubes, such as thermionic energy converters, are that they contaminate the surfaces of the cathode and anode, for example, and also increase the rate of re-combination of positive ions and electrons.

In tubes using low work function cathodes, such as ball-of-fire mode converters, the electron emitting surface 20 may, for example, be molybdenum, operating at a temperature of 1500° K., and having an absorbed partial coating of cesium and an effective work function of 2.2 volts. The anode may, for example, also be of molybdenum operating at a temperature of 800° K., and having a more complete coating of cesium and an effective work function of 1.7 volts. Any impurity gases in the tube in addition 25 to cesium vapor tend to contaminate the surfaces and change the effective work functions thereof. Even in tubes having cathodes operating at very high temperatures, and consequently no absorbed gas, the anode surfaces are contaminated by impurity gases.

40 In any electron tube, such as a thermionic energy converter, that depends upon a continuous supply of positive ions in the interelectrode space, to neutralize the space charge of the electrons, for example, it is obviously necessary to keep the rate of re-combination of positive ions and electrons as low as possible. It is believed that impurity gases tend to increase the re-combination rate.

Prior methods of making and processing metal vapor tubes have involved assembling the tube, evacuating it 45 to a high vacuum, baking the tube to out-gas the parts while continuing the evacuation, sealing off the tube from the pump, and then introducing the metal vapor into the tube in some manner. A disadvantage of this method is that the metal vapor when introduced attacks the internal surfaces releasing additional gases that are not 50 removed but remain as impurities. Moreover, during operation of the tube further gases are released, particularly from the hot cathode.

The principal object of the present invention is to provide a method and means for effectively removing gases 55 from a sealed electron tube envelope without permanently removing a desired gas.

Another object is to provide a new and improved method of processing a metal vapor tube.

60 A further object is to provide a novel electron tube having means for removing impurity gases and means for filling the tube with a desired gas.

65 These and other objects are achieved in accordance with one embodiment of the invention by providing a sealed electron tube envelope with a main body portion and at least first and second appendages, condensing a desired gas in the first appendage while heating the rest

of the tube, then condensing undesired impurity gases in an end portion of the second appendage while heating the body portion of the tube to out-gas the interior surfaces, then sealing-off the second appendage with the impurity gases trapped therein, and then evaporating the desired gas from the first appendage into the body portion of the tube.

In another embodiment of the invention, a sealed electron tube envelope is provided with an appendage, in which substantially all the gas in the envelope is condensed and removed by sealing-off the appendage as in the previously described embodiment, and then a sealed metal vapor capsule, which may be located in another appendage, is broken by external means after the gases are removed to supply metal vapor within the envelope.

In the accompanying drawings:

FIG. 1 is a side elevational view, partly in section, of an electron tube of the invention having two empty appendages;

FIG. 2 is a similar view of the tube of FIG. 1 combined with a cold trap;

FIG. 3 is a similar view showing the step of sealing-off one appendage;

FIG. 4 is a similar view of a modified tube having three appendages;

FIG. 5 is a similar view of a modification in which one appendage contains a metal vapor capsule; and,

FIG. 6 is an axial sectional view of a typical thermionic energy converter tube.

FIGS. 1, 2, 3 and 6 show an embodiment of the invention in which a thermionic energy converter tube 1 comprises a sealed envelope 3 including a main cylindrical body portion 5 and two empty tubular appendages 7 and 9 of different (initial) length sealed at their outer ends. Preferably, the appendage 9 is made up of a short section 11 of a malleable metal, such as copper, sealed to the body portion, and a long section 13 of stainless steel brazed to the short section 11.

As shown in FIG. 6, the body portion 5 of the envelope 3 may, for example, comprise two cylindrical or tubular metal sections 15 and 17 sealed to a ceramic ring 19 and two metal end plates 21 and 23. In the example shown, the end plates 21 and 23 include two cup-shaped re-entrant portions 21' and 23' which form the cathode and anode, respectively, of the tube. The side walls of the portions 21' and 23' may be made very thin and/or of a low heat conducting material to serve as heat dams for the cathode and anode. The numerals 25 and 27 indicate partial coatings of alkali metal which are formed on the surfaces of the cathode and anode 21' and 23', respectively, during operation. In the operation of the converter tube, the cathode 21' may be heated externally, as by a flame, solar heat, etc., and the anode 23' may be cooled to the desired temperature by suitable external means. The operating temperature of the cathode may be any value between 1400° and 2200° K. depending on the mode of operation of the tube.

The converter tube 1 is manufactured initially with a small amount of cesium, or other alkali metal, shown schematically at 29 in FIG. 1, within the envelope 3.

The tube 1 is processed, either immediately after being sealed off during manufacture or after a period of normal operation, to remove traces of impurity gases from the envelope. In the first step in this processing, the entire tube 1 is heated to vaporize the cesium, and then the shorter appendage 7 is cooled, as by insertion into a water cooling pipe coil 31, while the body portion 5 and longer appendage 9 are kept hot, to condense most of the cesium vapor on the inner wall of the appendage 7. As shown in FIG. 1, the body portion 5 may be heated by an electric current passed through a coil 33, and the appendage 9 may be directly heated by connecting the ends thereof to a voltage source 35. The temperatures are not critical except that the cooling temperature should not be appre-

ciable lower than the condensing temperature of cesium, to avoid condensing other gases or vapors of lower condensing temperatures. For example, the appendage 7 may be cooled to about 290° K. and the rest of the tube 5 may be heated to about 400° K., or higher.

After the cesium vapor has been condensed in appendage 7, the source 35 is disconnected and the longer appendage 9 is partially immersed in a cold trap 37, as shown in FIG. 2, to condense other gases contained in the envelope into the immersed end portion of the appendage. During this step, the appendage 7 is kept cool, to continue trapping the cesium therein, and the body portion 5 is heated to at least 600° K. and the cathode 21' and anode 23' are heated to temperatures above their normal operating temperatures, to out-gas the body portion 5 and the electrodes. The cold trap 37 may contain (1) liquid nitrogen (about 77° K.), or (2) liquid helium (about 4° K.), depending on the degree of evacuation desired. In order to remove all gases including helium, it would be necessary to use a closed liquid helium trap and pump the liquid helium at least to its lambda point, about 2° K. A liquid nitrogen trap is adequate to remove some of the impurity gases that are detrimental in thermionic energy converter tubes.

As soon as the impurity gases have been condensed in appendage 9, which requires only about fifteen minutes, the appendage 9 is sealed-off, as by cold pinch-off of the copper section 11, as shown in FIG. 3, thus permanently removing the outer end of the appendage with the condensed impurity gases trapped therein. The tube, thus purified by the removal of impurity gases, can now be used or operated without further processing, since the envelope including the appendage 7 containing the trapped cesium will normally become hot enough to vaporize the cesium. On the other hand, the entire envelope can be heated (after removing the cooling coil 31) to a temperature of at least 425° K., as a continuation of the processing described above, to restore the cesium vapor within the envelope.

If the appendage 9 in FIG. 1 were made long enough, the process described above could be repeated, to process the tube more than once; but this would ordinarily be impractical because the cold trap may be as much as 35 inches long. Instead, the tube can be provided with one or more additional trap appendages for this purpose. FIG. 4 shows a tube 41 having a body portion 5 and two appendages 7 and 9, as in FIGS. 1-3, plus another long appendage 43, to permit two successive processing operations.

FIG. 5 shows a converter tube 51 which may be identical with the tube 1 in FIGS. 1-3 and 6 except for the fact that appendage 7 contains a sealed metal capsule containing purified cesium, or other alkali metal, and the envelope 3 may or may not contain free cesium initially.

The tube 51 is processed in accordance with the invention in the following manner. First, the entire tube envelope is heated to a temperature sufficient to vaporize any free cesium contained therein and the end of appendage 9 is immersed in a cold trap, similar to trap 37 in FIG. 2. The body portion 5 and appendage 7 are then heated to at least 600° K. and the cathode and anode of the tube are heated to temperatures above their normal operating temperatures, to out-gas the envelope and electrodes, and then the appendage 9 is sealed-off as in FIG. 3. Next, the capsule 53 is broken, as by mechanically deforming and then heating the appendage 7, to release fresh cesium into the envelope. The entire envelope is subsequently heated to the desired temperature in order to obtain the necessary cesium pressure. For example, in operation in the ball-of-fire mode, the cesium vapor pressure may be from 1 to 10 mm. of Hg.

Other alkali metals can be used in practicing the invention, but cesium is preferred because it has the lowest ionization potential and work function.

What is claimed is:

1. A method of processing a sealed electron tube envelope containing a desired gas and an undesired gas having a lower condensing temperature than said desired gas and comprising a main body portion and two appendages, comprising the steps of:

- (a) selectively condensing most of said desired gas in one of said appendages at a temperature at least as low as the condensing temperature of said desired gas and higher than the condensing temperature of said undesired gas; and
- (b) condensing most of said undesired gas in the other appendage only at a temperature lower than said predetermined temperature.

2. A method of processing a sealed electron tube envelope containing a quantity of desired gas which will condense within said envelope at a given temperature and an undesired gas having a condensing temperature lower than said given temperature, and comprising a main body portion and two appendages, comprising the steps of:

- (a) selectively condensing most of said desired gas in one of said appendages at a temperature between said given and said lower condensing temperatures;
- (b) then condensing most of said undesired gas in an end portion of the other appendage temperature at least as low as said lower condensing temperature; and
- (c) then sealing-off said other appendage between said end portion and said body portion.

3. A method of processing a sealed electron tube envelope containing a quantity of desired gas and a quantity of an undesired gas having a lower condensing temperature than said desired gas, and comprising a main body portion and two appendages, comprising the steps of:

- (a) selectively condensing most of said desired gas in one of said appendages at a temperature at least as low as the condensing temperature of said desired gas, but higher than the condensing temperature of said undesired gas;
- (b) then condensing most of said undesired gas in an end portion of the other appendage at a temperature at least as low as the condensing temperature of said undesired gas;
- (c) then sealing-off said other appendage between said end portion and said body portion; and
- (d) then evaporating said desired gas from said one appendage into said body portion.

4. A method of selectively removing impurity gases from a sealed electron tube containing a vaporizable metal and an impurity gas and comprising a main body portion and two appendages, comprising the steps of:

- (a) heating said envelope to vaporize said metal;
- (b) condensing most of the metal vapor in one of said appendages at a predetermined temperature; and
- (c) condensing most of said impurity gas in the other appendage at a temperature lower than said predetermined temperature.

5. A method of selectively removing impurity gases from a sealed electron tube envelope containing a vaporizable metal having a relatively high condensing temperature and an impurity gas having a relatively low condensing temperature and comprising a main body portion and two appendages, comprising the steps of:

- (a) heating said envelope to vaporize said metal, and condensing most of the metal vapor in one of said appendages at a temperature intermediate said relatively high and said relatively low temperatures;
- (b) then condensing most of said impurity gas in an end portion of the other appendage at a temperature at least as low as said relatively low temperature; and
- (c) then sealing-off said other appendage between said end portion and said body portion.

6. A method of selectively removing impurity gases from a sealed electron tube envelope containing a vapor-

75

izable metal and an impurity gas and comprising a main body portion and two appendages, comprising the steps of:

- (a) heating said envelope to vaporize said metal, and cooling a portion of one of said appendages to a temperature at which most of the metal vapor is condensed therein;
- (b) then cooling an end portion of the other of said appendages to a temperature at which most of said impurity gas is condensed therein; and
- (c) then sealing-off said other appendage between said end portion and said body portion.

7. A method of selectively removing impurity gases from a sealed electron tube envelope containing a vaporizable metal and an impurity gas and comprising a main body portion and two appendages, comprising the steps of:

- (a) heating said envelope to vaporize said metal, and cooling a portion of one of said appendages to a temperature at which most of the metal vapor is condensed therein;
- (b) then cooling an end portion of the other of said appendages to a temperature at which most of said impurity gas is condensed therein;
- (c) then sealing-off said other appendage between said end portion and said body portion; and
- (d) then vaporizing said metal vapor from said one appendage into said body portion.

8. A method of selectively removing impurity gases from a sealed electron tube envelope containing a vaporizable metal and an impurity gas and comprising a main body portion and two appendages, comprising the steps:

- (a) heating said envelope to vaporize said metal, and cooling a portion of one of said appendages to a temperature at which most of the metal vapor is condensed therein;
- (b) then heating said body portion to a temperature of at least 600° K. to de-gas the same, while cooling an end portion of the other of said appendages to a temperature at which most of said impurity gas is condensed therein; and
- (c) then sealing-off said other appendage between said end portion and said body portion.

9. A method of selectively removing impurity gases from a sealed electron tube envelope containing cesium and an impurity gas and comprising a main body portion containing a plurality of electrodes and two tubular appendages, comprising the steps of:

- (a) heating said envelope to a temperature of about 400° K. to vaporize said cesium;
- (b) then cooling a portion of one of said appendages to a temperature of about 290° K. to condense most of the cesium vapor therein, while maintaining said body portion and other appendage at said first-named temperature;
- (c) then cooling an end portion of the other of said appendages to a temperature between 2° and 77° K. to condense most of said impurity gases therein, while heating said body portion to a temperature of at least 600° K. and said electrodes to temperatures slightly above their normal operating temperatures to de-gas the same, and maintaining said first-named portion at said second-named temperature;
- (d) then sealing-off said other appendage between said end portion and said body portion; and
- (e) then heating said one appendage to a temperature of at least 425° K. to vaporize cesium into said body portion.

10. A method of selectively removing impurity gases from a sealed electron tube envelope containing cesium and impurity gases and comprising a main body portion and two appendages, comprising the steps of:

- (a) heating said envelope to vaporize said cesium, and cooling a portion of one of said appendages to a

- temperature at which most of the cesium vapor is condensed therein;
- (b) then heating said body portion to a temperature of at least 600° K. to de-gas the same, while immersing an end portion of the other of said appendages in a liquid helium trap to condense most of said impurity gases in said end portion; and
- (c) then sealing-off said other appendage above the liquid level in said trap.

11. A method of processing a sealed electron tube envelope containing a sealed metal vapor capsule and impurity gases and comprising a main body portion and an appendage, comprising the steps of:

- (a) heating said envelope to de-gas the same, and condensing most of the said impurity gases within an end portion of said appendage;
- (b) then sealing off said appendage between said end portion and said body portion; and
- (c) then releasing metal vapor from said capsule into said envelope.

12. A method of processing a sealed electron tube envelope containing impurity gases and comprising a main

body portion and two appendages, one of which contains a sealed cesium capsule, comprising the steps of:

- (a) heating said envelope to de-gas the same, and condensing most of said impurity gases within an end portion of the other of said appendages;
- (b) then sealing-off said other appendage between said end portion and said body portion; and
- (c) then releasing cesium vapor from said capsule into said body portion.
